DESIGN FOR A TOY DOLL

Jacob Swedlin, Brooklyn, N. Y., assignor to J. Swedlin, Inc., New York, N. Y., a corporation of New York

Application April 29, 1937, Serial No. 69,040

Term of patent 7 years

To all whom it may concern:

Be it known that I, Jacob Swedlin, a citizen of the United States, residing in Brooklyn, in the county of Kings and State of New York, have invented a new, original, and ornamental Design for a Toy Doll, of which the following is a specification, reference being had to the accompanying drawings, forming a part thereof.

Fig. 1 is a front perspective view of a toy doll, showing my new design.

Fig. 2 is a perspective view of the same as viewed from the rear.

I claim:

The ornamental design for a toy doll, as shown.
JACOB SWEDLIN.
